MOP HEAD

Zolly C. Van Schwartz, Englewood, Colo., assignor to Majestic Wax Company, Denver, Colo., a corporation of Colorado

Filed Sept. 3, 1963, Ser. No. 76,451

Term of patent 14 years

(Cl. D9—2)

The essential features of my design reside in the portions shown in full lines, the broken line showing of the handle socket, the mop strands and the clips being omitted in FIGURES 2—7 for convenience of illustration.

I claim:

The ornamental design for a mop head, as shown and described.
